UNITED STATES PATENT OFFICE.

WILLIAM JOHN FOWLER, OF PHILADELPHIA, PENNSYLVANIA.

SAFETY LOCKING DEVICE.

1,157,523.

Specification of Letters Patent. Patented Oct. 19, 1915.

Application filed April 16, 1915. Serial No. 21,746.

To all whom it may concern:

Be it known that I, WILLIAM JOHN FOWLER, a subject of the King of Great Britain, residing at Philadelphia, in the county of Philadelphia and State of Pennsylvania, have invented new and useful Improvements in Safety Locking Devices, of which the following is a specification.

This invention relates to an improved safety locking device for the emergency brake levers of an automobile.

The invention has for its object to produce a simple and improved automatic device whereby when the emergency brake lever is set to exert the maximum amount of resistance, it will be locked in such position and be incapable of being released except by the use of a special key provided for the purpose.

A further object of the invention is to simplify and improve the construction and arrangement of parts whereby the emergency lever will be locked in "set" position, as above indicated.

With these and other ends in view which will readily appear as the nature of the invention is better understood, the same consists in the improved construction and novel arrangement and combination of parts which will be hereinafter fully described and particularly pointed out in the claim.

In the accompanying drawing has been illustrated a simple and preferred form of the invention, it being, however, understood that no limitation is necessarily made to the precise structural details therein exhibited, but that changes, alterations and modifications within the scope of the claim may be resorted to when desired. In the drawing, Figure 1 is a side elevation, partly in section, of an emergency lever to which the invention has been applied. Fig. 2 is a sectional view taken on the line 2—2 in Fig. 1. Fig. 3 is a vertical sectional view of the handle portion of the lever.

Corresponding parts in the several figures are denoted by like characters of reference.

The emergency lever 15 which is fulcrumed at 16 is provided at its lower end with a pawl 17 adapted to engage a ratchet segment 18 which is mounted on a support 19 which also supports the bracket 20 on which the lever 15 is fulcrumed. For the purpose of actuating the pawl 17 a rod 21 is provided which slidably engages the lever 15, the latter being provided with keepers

22 wherein the rod is guided. The rod 21, which is pivotally connected with the pawl 17, at 23, is actuated in an upward direction by a spring 24, thus maintaining the pawl normally in engagement with the teeth of the ratchet bar.

The handle 25 at the upper end of the lever 15 is provided with a socket 26 through which the upper end of the rod 21 extends, the handle 25 being preferably offset from the body of the lever, as seen at 27, so as to place the socket 26 in alinement with the rod. The upper end of the rod 21 which extends through and above the socket 26 is provided with a portion of enlarged diameter 28 and with a push button 29. The enlarged portion 28 has an annular groove 30 adapted to be engaged by a spring actuated pin or bolt 31 which is housed in the handle member 25, said bolt being adapted to be retracted against the tension of its actuating spring 32 so as to release it from engagement with the groove 30 by means of a key 33 for the admission of which a keyhole 34 is provided.

The notches or interspaces between the teeth 35 of the ratchet bar 18 are all of approximately equal depth, except the last or final notch 36 of the series, which is not engaged by the pawl 17 until the lever is set to its maximum extent. The parts of the device are so arranged and proportioned that when the pawl 17 engages any of the notches or interspaces between the teeth 35 except the final notch 36, the annular groove 30 in the enlarged portion of the rod 21 will be positioned below the locking bolt or pin 31 so as to be incapable of being engaged thereby. The last or final notch 36, however, is of such a depth that when the pawl 17 engages the same, the spring 24 will force the rod 21 upwardly to such an extent that the annular groove 30 will be placed in registry with the pin or bolt 31 and be engaged thereby. The rod will thus be held with perfect security against downward movement until the bolt 31 is retracted by the key provided for the purpose, and the emergency lever will thus be securely locked until released by a person provided with a proper key for the purpose.

Having thus described the invention, what is claimed as new, is:—

An emergency brake lever having a pawl, and a segmental ratchet bar engaged by said pawl, said bar having at one end a notch of

materially greater depth than the remaining notches or interspaces between the teeth thereof, a spring actuated rod for actuating the pawl, and a detent arranged to engage said rod when the pawl engages the notch of special depth, such engagement producing a movement of the rod of greater extent

than when the pawl engages any one of the remaining notches.

In testimony whereof I affix my signature 10
in presence of a witness.

WILLIAM JOHN FOWLER.

Witness:

HELEN G. DALEY.
